ANNEALING COVER

Edward N. Millan, Middletown, Ohio, assignor
to The American Rolling Mill Company,
Middletown, Ohio, a corporation of Ohio

Application August 26, 1935, Serial No. 37,858

7 Claims. (Cl. 263—49)

My invention relates to annealing covers for covering packs of sheet metal or coils while they are being heat treated, and is a continuation in part of my copending application Serial No. 5 3,083, filed January 23, 1935. The uses of annealing covers are well known, and particular description thereof is not necessary. The employment of annealing covers to retain particular atmospheres surrounding the pieces being heat 10 treated is also well known. Because of their uses, annealing covers should be relatively rigid, but at the same time they should be as light as possible, both for convenience in handling and also for efficient heat transfer. This desirable 15 lightness has not been attained in the cast annealing covers in current use. It has hitherto for the most part been considered necessary to provide a great bulk of metal to give satisfactory rigidity under high heats. Because of the rough 20 usage and the great heat to which annealing covers are subjected, they must of course be very rugged and strong. Another difficulty present where gaseous media under pressure are introduced into the box while hot, is that there is 25 a tendency for the sides to bulge. The rough handling to which such covers are subjected also has a tendency to cause the roof to sag.

It is an object of my invention to provide an annealing cover which is extremely strong and 30 rigid and capable of forming a gas tight chamber, and very resistant to heat and wear, but which is at the same time light in weight.

It is a further object of my invention to provide annealing covers which are relatively inexpensive to construct but which when constructed have all of the above advantages.

Another object of my invention is to provide annealing covers having the above mentioned desirable qualities which may be constructed with 40 a minimum of welding.

Still another object of my invention is to provide annealing covers of such a construction that the tendency of the covers to bulge outwardly under the influence of hot gases is neutralized.

These and other objects of my invention which will be set forth hereinafter, or will be apparent to one skilled in the art upon reading these specifications, I accomplish by that certain construction and arrangement of parts of which I shall now describe a preferred embodiment. Reference is made to the drawings which form a part hereof, and in which:

Figure 1 is an end elevation with part cut away, 55 of my annealing cover.

Figure 2 is a side elevation of the same with part cut away.

Figure 3 is view corresponding to Figure 1 of a modified construction.

Figure 4 is a side elevation of the modified 5 construction of Figure 3, corresponding to Figure 2.

Figure 5 is a section taken on the line 5—5 of Figure 2.

Figure 6 is an end elevation with part cut 10 away of a modification of my cover.

Figure 7 is a side elevation of the same with part cut away.

Broadly my invention comprises providing an 15 annealing cover formed of relatively heavy corrugated metal sheets welded together to form the desired sealed chamber. The corrugated sheets which I prefer to use are of rough plate, by which I mean the product of the modern 20 continuous mill, which is of a weight of 8 to 12 gauge or thereabouts, and are welded together with strengthening struts or bands where desired, to form a chamber, with sides, ends and a top, to fit over a pack or stack of sheets while they are being annealed.

I prefer to use an alloy containing 15% or 25 more of chromium, and 85% or less of iron. I may further use an alloy containing 25% 30 chromium, 12% nickel, and 63% iron. However, variations in the percentage of metals used in the alloys may be made without departing from the scope of my invention.

Briefly, in the practice of my invention, I provide a chamber or annealing cover having four 35 sides 1, 2, 3 and 4 formed of a relatively heavy corrugated sheet metal. These side pieces 1, 2, 3 and 4 are so positioned as to form a hollow rectangle with the corrugations 5 vertical and with the ends of the sheets abutting. These ends are preferably welded to each other so as to 40 form an integral unit of the sides 1, 2, 3, and 4, all as described in my copending application hereinabove referred to.

The corrugated pieces which I prefer to use are made of rough plate as above described, or similar material of 8 to 12 gauge, or thereabouts, corrugated with large corrugations between rolls in the direction of the shorter dimensions of the sheets, say with corrugations having a depth of substantially 1½ inches and a pitch of six inches, and where the corrugated pieces are to be curved, this is done progressively between dies. The figures given are, of course, exemplary and not 45 limiting.

About the lower edges of the four sides 1, 2, 3 and 4, I place four strips of iron 8, and weld them to the lower edges of the said sides along their contacting portions. The ends of the four irons 8 may be beveled and welded to each other in order to form an integral frame. The welding may be done in any convenient commercial way, as by electricity or flame.

The top portion 12 is in the shape of an arch and is fastened to the side walls 1 and 3 by means of strips 13 of metal welded to the ends of the corrugations 5. These strips 13 are wider than the end of the corrugations 5 of the side walls and a portion 14 of them is permitted to project over the side walls 1 and 3 and into the chamber. This portion 14 is bent over so as to contact the ends of the corrugations of the bent portion of the top 12, and at a right angle to the same. In other words if the top 12 is a portion of the segment of a circle, the bent portions 14 would define a radial line of the same circle. Bending the portions 14 in this manner, greatly facilitates construction since it is possible to form the top 12 of a sheet of corrugated metal with vertical or square cut ends, and then to bend this top 12 into the predetermined arc. This in turn will bring the ends of the corrugations 5a of the top 12 into registry with the surface of the bent-over portion 14, to facilitate welding. The two ends or side walls 2 and 4 are so configured at their top edges that they will contact the underside of the top 12 when it is in position. Hooks 18 may be welded to the ends or sides of the cover shown in Figure 2 as illustrated, for the purpose of handling.

In the modified construction illustrated in Figures 3 and 4, I have eliminated the members 13, and have somewhat altered the form of the arch. In this embodiment I form the arch 12a from a flat plate, i. e. not corrugated, and curve it so as to fit the curved upper ends of the end walls. Along the sides I flatten out lips 13a and turn them outward until they are in a horizontal plane. The roof section is then simply set on top of the side and end walls and welded thereto, the lip 13a taking the place of the member 13 of Figures 1, 2 and 5.

In order to prevent sagging of the roof I may provide the plates 6. These plates are cut out along one edge to conform to the curvature of the arch, and along the other edge there is formed an angle leg 6a at right angles to the plane of the supporting plate. The plate 6 is welded in several places along the line of contact between the plate and the arch, and the angle leg 6a gives it strength in a transverse direction.

As pointed out above, a tendency has been noted for the side walls of the annealing cover to bulge outwardly due to the gaseous pressure on the inside. To neutralize this tendency I may make the annealing cover of pylon form, having a larger area at the base than at the top, by inclining the side and end walls inwardly, as shown at 1a, 2a, 3a and 4a in Figures 6 and 7. There is a normal tendency in this construction for the walls to sag inwardly, and by proper design, the sagging tendency may be made to neutralize the aforementioned bulging tendency.

The amount of inclination given to the side and end walls will depend on (a) the temperature at which the box is to be used, and (b) the pressure of the introduced medium. The amount that the base dimensions exceed the top dimensions may thus vary from zero to 20%, depending upon factors (a) and (b).

The different configurations and shapes of the cover shown in my drawings are not intended as a limitation, since numerous other forms may be used without departing from the spirit of my invention.

Having thus described my invention, what I claim as new and desire to secure by Letters Patent, is:—

1. An annealing cover comprising vertically corrugated side wall members of plate metal, an arc shaped top of laterally corrugated plate metal and a joining strip therebetween, said strip longitudinally bent to form an obtuse angle one leg of which overlies and is welded to the top of the side wall, and the other leg of which is placed flatwise against the end of the top and welded thereto.

2. An annealing cover comprising corrugated side wall members of plate metal, an arc shaped top of corrugated plate metal and a joining strip therebetween, said strip longitudinally bent to form an obtuse angle one leg of which overlies and is welded to the top of the side wall, and the other leg of which is placed flatwise against the end of the top and welded thereto.

3. An annealing cover comprising corrugated side wall members of plate metal, an arc shaped top of corrugated plate metal and a joining strip therebetween, said strip longitudinally bent to form an obtuse angle one leg of which overlies and is welded to the top of the side wall, and the other leg of which is disposed at an angle radial to the curvature of the top and welded to the end thereof.

4. An annealing cover according to claim 2, the side and end walls of which are of such proportions that the horizontal cross sectional area of said cover at its top is smaller and similar to its horizontal cross sectional area at its base.

5. An annealing cover comprising corrugated trapezoidal side wall members of plate metal, an arc shaped top of corrugated plate metal and a joining strip longitudinally bent to form an obtuse angle one leg of which overlies and is welded to the top of the side wall, and the other leg of which is placed flatwise against the end of the top and welded thereto.

6. An annealing cover according to claim 2, the side walls of which are of such proportion that the horizontal cross sectional area of said cover at its top is smaller than its horizontal cross sectional area at its base.

7. An annealing cover according to claim 2, the end walls of which are of such proportion that the horizontal cross sectional area of said cover at its top is smaller than its horizontal cross sectional area at its base.

EDWARD N. MILLAN.
